UNITED STATES PATENT OFFICE.

JOSEPH DICK, OF CANTON, OHIO.

DESIGN FOR A FLY-WHEEL.

SPECIFICATION forming part of Design No. 35,153, dated October 1, 1901.

Application filed August 14, 1901. Serial No. 72,080. Term of patent 14 years.

To all whom it may concern:

Be it known that I, JOSEPH DICK, a citizen of the United States, residing at Canton, in the county of Stark and State of Ohio, have 5 invented and produced a new and original Design for Fly-Wheels, of which the following is a specification.

The invention relates to a new and original design for a fly-wheel for pneumatic conveyors; and it consists of the design of the configuration shown in the accompanying drawings, in which—

Figure 1 is a perspective view, and Fig. 2 is a front elevation.

15 Referring to the drawings, 1 denotes the disk-shaped body portion of the wheel, hav-

ing a hub 2. Projecting from the periphery of the body portion of the wheel are blades 4, which appear to straddle the wheel and are provided with braces 5, which extend diagonally from the blades and also appear to straddle the wheel.

What I claim is—

The design for a fly-wheel, as herein shown and described.

In testimony whereof I have hereunto set my hand in the presence of two subscribing witnesses.

JOSEPH DICK.
